UNITED STATES PATENT OFFICE.

WILLIAM B. HARTNETT, OF BROOKLYN, NEW YORK.

DESIGN FOR A PATRIOTIC BADGE OR PENDANT.

51,015.

Specification for Design.

Patented July 10, 1917.

Application filed May 8, 1917. Serial No. 167,366. Term of patent 3½ years.

To all whom it may concern:

Be it known that I, WILLIAM B. HARTNETT, a citizen of the United States, residing at Brooklyn, in the county of Kings and State of New York, have invented a new, original, and ornamental Design for a Patriotic Badge or Pendant, of which the following is a specification, reference being had to the accompanying drawing, forming part thereof.

The figure is a front elevation of a patriotic badge or pendant, showing my new design.

I claim:

The ornamental design for a patriotic badge or pendant, as shown.

WILLIAM B. HARTNETT.
